UNITED STATES PATENT OFFICE.

JOSEPH SCHMIDT, JR., OF CHICAGO, ILLINOIS, ASSIGNOR TO JOHN L. FLANNERY, OF CHICAGO, ILLINOIS.

BOX-STAPLING MACHINE.

SPECIFICATION forming part of Letters Patent No. 694,031, dated February 25, 1902.

Application filed March 29, 1901. Serial No. 53,426. (No model.)

To all whom it may concern:

Be it known that I, JOSEPH SCHMIDT, Jr., a citizen of the United States, residing at Chicago, in the county of Cook and State of Illinois, have invented certain new and useful Improvements in Box-Stapling Machines; and I do hereby declare the following to be a full, clear, and exact description of the invention, such as will enable others skilled in the art to which it appertains to make and use the same.

This invention relates to a machine for use in the manufacture of boxes and like receptacles, and has for its object to provide a device of this character that is more especially intended for stapling three corners of a box-frame at one operation, as will be hereinafter set forth in detail.

The operation of stapling the three corners of a box-frame is performed when the box blank or board is supported in a flat horizontal position. The different sections representing the respective sides of a box are then folded at right angles and the frame portion of the structure completed by fastening the joining ends forming the fourth or closing corner.

In the drawings, Figure 1 is a front elevation of a machine embodying the operative features. Fig. 2 is an end elevation looking at the right-hand end of Fig. 1. Fig. 3 is a vertical transverse section and part elevation on line 3, Fig. 1, looking in the direction indicated by the arrow. Fig. 4 is a vertical transverse section on line 4, Fig. 1. Fig. 5 is a longitudinal horizontal section on line 5, Fig. 1. Fig. 6 is an edge view of a board box-blank provided with kerfs preparatory to the stapling operation. Fig. 7 is an elevation of one of the driving-heads. Fig. 8 is a vertical section on line 8, Fig. 7. Fig. 9 is a broken vertical section on line 9, Fig. 7. Fig. 10 is a similar view on line 10, Fig. 7. Fig. 11 is a horizontal section on line 11, Figs. 7 and 8. Fig. 12 is a horizontal section on line 12, Figs. 7 and 8. Fig. 13 is a horizontal section on line 13, Figs. 7 and 8. Fig. 14 is a broken-away detail of the wire-cutting and staple-forming mechanism. Fig. 15 is an elevation and part section of the clenching mechanism. Fig. 16 is a horizontal section on line 16, Fig. 15; and Fig. 17 is a view in perspective of a box-frame folded and ready for the final operation of fastening the fourth or closing corner.

The main supporting-frame consists of the 55 respective ends A A', the connecting top beams B B, the upper front bar C, the corresponding back bar C', and the lower front and back bars D and D'. The companion bars 2 and 3 run longitudinally with reference to the main frame and have their respective ends rigidly secured in the companion heads 4 and 5, for which guide-bearings 6 are provided, adapting the same to have a vertical movement in the respective ends of 65 the frame.

A number of cross-heads 7 are mounted on the bars 2 and 3 and are longitudinally adjustable thereon. In this instance three cross-heads are shown in position, Fig. 1, the 70 interval or space between each corresponding to the relative position of three corners of a box-frame. The respective ends of a rod 8 are secured in the lower bifurcated ends of each of the cross-heads, as shown in Figs. 1 75 and 3. A number of driving-heads 9 are adjustably mounted on the rod or rods 8. The number of driving-heads mounted in each of the cross-heads 7 will be in accordance with the dimensions of the box-receptacle and the 80 number of staples to be inserted in the respective corner-joints, each driving-head inserting one staple and all being inserted simultaneously with one down movement of the mechanism. The driving-heads are positioned with reference to each other in accordance with the setting distance between staples.

The driving-heads are made up of a number of parts, and a description of one head 90 will apply to all. The different parts comprise a clip 10, adjustably mounted on the cross-head rods 8, a staple-driver 11, wire-cutting and staple-forming bars 12 and 13, which flank the driver, and other elements 95 that will be hereinafter referred to. The cutting and forming bars of each driving-head are loosely framed in the back guides 14, which are adjustably secured between transverse bars 15 and 16, provided longitudinally 100 with slots 17, Fig. 3, through which the adjusting and locking bolts 18 are inserted. This arrangement provides for positioning the back guides 14 in line with the other parts of the driving-heads as the clips 10 are shifted 105 transversely on their supporting-rods 8. The ends of the transverse bars 15 and 16 are secured to the end plates 19 and 20 by a num-

ber of bolts 21. The front and back frame-bars C and C' are provided longitudinally with slots 22, Figs. 1 and 3, through which are inserted adjusting and locking bolts 23, 5 entering the respective end plates 19 and 20, and provides for the adjusting of each group of driving-heads either nearer to or farther apart with reference to the longitudinal dimensions of the machine and in accordance 10 with the distance to be maintained between each row of staples.

Companion bearing-pins 24 and 25 are inserted in the heads 4 and 5 at each end of the machine. The upper ends of the companion 15 connecting-rods 26 and 27 are properly joined to the bearing-pins. The lower strap ends of these connecting-rods engage eccentrics 28 and 29, which are mounted on the respective ends of a driving-shaft 30. This provides 20 the operative connection for transmitting the up-and-down movement to each group of driving-heads simultaneously.

The bars 12 and 13 possess the dual function of cutting off the wire and forming the 25 staples and move in advance of the driver or drivers on the downstroke. These bars are connected at their upper ends by a transverse bar 31, as shown in Figs. 7 and 8. In these last figures the different parts of the 30 driving-head are shown in their normal position. In Fig. 7 the upper end of the staple-driver is shown broken away. In Fig. 3 the upper end is shown connected to clip 10, as at 32.

35 The upper ends of curved companion arms 33 and 34 are pivoted to the driver, as at 35. Down below their pivotal point these arms are each provided with a beveled shoulder 36, which is adapted to have an intermittent engagement with notches 37, formed in the upper edges and ends of the cross-bar 31, connecting the cutting and forming bars. By this means the down movement of the driver is transmitted to the cutting-bars, which keep 45 the advanced position, Fig. 7, until the staple has been formed.

A face or cap plate 38 (shown in Fig. 8, but omitted in Fig. 7) is removably attached to the front side of the back guide 14 and is provided on its upper end and opposite edges with a beveled surface 39, as indicated by a dotted line in Fig. 7.

The down movement of the cutting and forming bars is arrested at the proper time 55 by the lower ends 40 of the curved arms coming in contact with the beveled sloping surface 39, which has the effect of imparting a lateral movement to the curved arms and spreading them far enough apart to disengage the same from the cross-bar 31, the down movement of the driver continuing until the staple is inserted.

The inner ends of two spiral springs 41 and 42 are connected to a ring 43, fixed in the 65 driver, the outer ends of these springs connecting with the curved arms, as at a, and serving to return the same to their normal en-

gaged position with the cross-bar 31 on the up movement of the driving mechanism and ready for the next down movement.

The lower part of the driver is provided on its respective edges with a rib 44, Fig. 7, which terminates with the lower end of the driver. The adjacent edges of the cutter-bars are provided with a groove 45, Fig. 14, 75 with which the ribs 44 engage. The lower ends of the cutter-bars are beveled on both sides, as at 46, which form will have the effect of cutting off the wire and providing each end of the staple with a sharp beveled point, 80 so that it may be more easily driven.

An anvil 47, Figs. 7 and 8, is seated in an opening formed in the driving-head guide-plate. The front part of this anvil is provided with a beveled surface 48 and normally 85 is located in the path of the driver. The lower end of a spring 49 is secured to the anvil, Fig. 8, the upper end being secured to the rear side of the back guide 14, and serves to return the anvil to its normal position after 90 the driver has moved upward out of contact. The anvil is provided in the front side with a wire-groove 50, the wire strand 51, from which the staples are made, being shown in the groove.

95 A bolt 52 is inserted through the cross-bar of the cutter-bars and ends against the inner side of the back guide 14. The driver is provided with a slot-opening 53, so that its up-and-down movement will not be interfered with by the presence of bolt 52. The upper end of a compression-spring 54 is secured to this bolt, the lower end being secured to a bolt 55, fixed in the face-plate 38. When the driver has reached the end of its downstroke 105 and inserted the staple, it rests for a moment and during that moment has the function of an anvil for the operation of the clenching mechanism.

The wire from which the staples are made 110 enters on the side 56, Fig. 7, and passes through the groove in the anvil and through a movable wire-guide 57 into an aperture 58, Figs. 9 and 10, in the bottom die 59, having a V-groove 60 in the inner edge, as best shown in 115 Fig. 13. This groove corresponds to the double-beveled lower engaging end of the cutting-bar on that side. The normal position of guide 57 is in the path of the cutting-bar on that side and serves to guide the wire into 120 the aperture in the die member 59, from which it protrudes, as shown in Fig. 7. As the cutting-bar comes in contact with the beveled surfaces 61 of the wire-guide it forces the same back out of the way in order to engage the 125 wire in the operation of forming the staple. This guide is returned to its normal position after the cutting-bar has moved upward by a spring 62. (Shown in Fig. 9.) A lower companion die member 63 is provided for the cutting-bar on the opposite side, by which means both ends of the staple are cut off clean and sharpened, so as to more easily penetrate the work.

As the cutting-bars come in contact with and sever the wire and move down past the respective ends of the anvil the portion 64, bent around at right angles in forming the 5 rectangular staple 65, rests in the grooves 45 in the cutting and forming bars, as shown in Fig. 14. The staple is now ready for the contact of the driver, which is moving down, and as the driver comes in contact with the 10 beveled edge of the anvil it forces the same back out of its path and frees the staple therefrom and comes in contact with the back thereof, the ribs on the respective sides of the driver contacting the corners of the staple 15 resting in the lower part of the grooves in the adjacent edges of the cutting-bars, thus providing for a continuous bearing the full width of the staple and setting the same close into the surface of the work.

20 The length of wire fed in at each periodical movement of the feed mechanism is a little more than is required for a staple, which provides for the cutting and sharpening of both ends, the bit of waste wire remaining in the 25 die member 59 until ejected by the next entering end of the wire.

The clenching mechanism is located directly under the driving mechanism and is actuated by the same driving-shaft. A plurality of clenching devices are provided, one for each driving-head and set directly under and in line therewith, so that the operation of clenching is performed simultaneously with the insertion of the staple. The clenching 30 mechanism is adjustable both laterally and longitudinally to correspond to the adjustment of the driving mechanism and is supported in the lower front and back framing-bars D and D' of the main frame.

40 The clenching-mechanism frame consists of the companion side bars 66 and 67, Figs. 3, 15, and 16, and the two end pieces 68 and 69, to which the respective ends of the side bars are secured, as at 70. A plan of this supplementary frame is also shown in Fig. 5; but the clenching devices proper are omitted from this figure in order to avoid confusion. The holding and adjusting bolts 71 are inserted through longitudinal slots 72 in the front bar 45 D of the main frame and engage the end piece 68. The companion bolts 73 are inserted through the longitudinal slots 74 in the back bar D' of the main frame and engage the end piece 69. This arrangement provides for the longitudinal adjustment of the clenching-heads relatively in the same manner as that of the driving-heads.

50 The side bars 66 and 67 are provided longitudinally with slots 75, through which are inserted holding and adjusting bolts 76, engaging the respective sides of the clencher back guide 77, in which the clencher plate or plates 78 have a vertical movement. The clencher-plates are adjustably mounted on a cross-bar 79, forming a part of a lifting-yoke 80. The respective sides 81 of this yoke are rabbeted in the end pieces 68 and 69, Figs.

3 and 5, to retain the same in proper position and provide for the vertical movement thereof. The stem of the yoke is bifurcated at its 70 lower end and loosely embraces the driving-shaft, as shown at 82, Figs. 1 and 3.

The removable cap 83 (shown in place in Fig. 16, but omitted in Fig. 15) is provided with companion guide-pins 84, loosely engaging vertical companion slots 85 in the clenching-plate 78, so as to allow for a free movement and retain the clenching-plate in alignment at the same time. Two clencher-dogs 86 and 87 are pivoted at their outer ends, as 80 at 88, to the back guide 77. The inner loose ends of these dogs rest on the upper end of the clencher-plates, as shown in Fig. 15, all the parts being in their normal position ready for the up clenching movement. In Fig. 15 85 is also shown the relative position of the work and staple just inserted, the respective ends of which come in contact with the upper concave surface 89 of the dogs and are curved inwardly in the direction of each other, as 90 shown, the clencher mechanism being at rest. As the clencher-plate moves upwardly the dogs have a movement in the arc of a circle, and by reason of the higher surface between the point of the staple and pivot of the dogs a 95 drawing action is imparted to the ends of the staple and the same drawn inwardly and embedded in the inside surface of the work. The opposite clenched position of the dogs is indicated by dotted lines. This form of a dog 100 prevents the staple from backing out; but such action is also guarded against by so timing the movements of the different parts that the operation of clenching is completed before the pressure of the staple-driving heads 105 is relaxed.

The vertical movement of the yoke or yokes 80, carrying the series of clencher-heads, is effected by a cam-wheel 90, rigidly mounted on the driving-shaft adjacent to the stem of each yoke, Figs. 1 and 3. A bracket 91 is secured to each yoke-stem and has a roller 92 journaled therein and which has a rolling contact with the periphery of the cam-wheel 90. Each of the cam-wheels is provided on its periphery with a projection or raised part 93, Fig. 3, which is adapted to have an intermittent contact with the roller 92 and impart an up movement to the clenching mechanism. When the cam projection has passed out of 120 contact with the roller 92, the clenching mechanism returns to its lower normal position.

The wire from which the staples are made is taken directly from a spool or reel, and the wire-feed mechanism will be next described. 125

A motion-transmitting shaft 94 is mounted on the front side of the machine and has its respective ends provided with suitable bearings in the hangers 95, secured to the main frame, Figs. 1, 2, and 4. A transverse counter-shaft 96 is provided for each series of driving or stapling heads, Figs. 3 and 5, which extend along one side thereof and are journaled in hangers 97. A pinion 98 is mount-

ed on the front end of each of the counter-shafts. These pinions engage the companion pinions 99, disposed at intervals on shaft 94. A pinion 100 is mounted on one end of shaft 94, Figs. 1, 2, 4, and 5, with which the upper end of a rack-bar 101 engages. The lower end of this rack-bar is provided with a friction-roller 102, loosely engaging an elongated slot 103 in the outer end of a motion-transmitting link 104, the inner end of which is pivoted, as at 105, to one end of the main frame. The rack-bar is retained in its proper working position by a guide-lug 106. A cam-wheel 107 is rigidly mounted on the main driving-shaft, Figs. 1 and 4, and is provided on its rim with a raised part 108, which is adapted to have contact once in each revolution of the cam-wheel 107 with the link 104 and raise the outer end of the same upwardly, which has the effect of transmitting a corresponding movement to rack-bar 101 and rotating shaft 94, which in turn imparts a single impulse to the counter feed-shafts 96 in feeding just a sufficient length of wire with each impulse to form a staple.

A series of feed-rollers 109 is mounted on the feed-shafts in line with the driving-heads, as shown in Figs. 1 and 5. Above each of these feed-rollers and in line therewith are located tension or gripping rollers 110, journaled in the heel of a corresponding member of angle or bell-crank levers 111, pivoted at their lower ends to the face-plate of the driving-heads. A tension set-screw 112 (indicated by dotted lines in Fig. 1) is inserted through the upper ends of levers 111 and is tapped in the adjacent surface of the frame. By turning these screws in one direction the clamping pressure of the feed-rollers on the wire is increased, and turning the same in the opposite direction has the effect of diminishing the pressure, and thus the tension on the wire is easily regulated as may be required.

An edge view of the board-blank 113, forming the frame of a box, is shown in Fig. 6. The grooves or kerfs 114 are cut from the under side to the proper depth, leaving the extension-surface intact and spaced to indicate the position of the corners. Adjacent to Fig. 6 the blank is shown in position to be passed into the machine from the front side for the operation of stapling three of the corner-joints while the blank is held in the flat position shown. The blank is inserted in the machine through the space 115 separating the driving and clenching mechanism and is supported on the frame-surface of the latter, which forms a table-bed therefor in the operation of stapling. At the rear side of the machine, Fig. 5, the blank is shown after having passed through, the different staples in each of the rows being simultaneously inserted. In the next step the sections forming the different sides of the box are bent around at right angles, the two beveled ends 116 of the blank forming the fourth or closing corner, and is stapled on a machine like that shown

in my application filed April 4, 1900, Serial No. 11,462.

Having thus described my invention, what I claim as new, and desire to secure by Letters Patent, is—

1. In a box-stapling machine, the combination with the main frame, of the longitudinal companion bars, the companion heads, mounted on the respective ends of said bars, the guide-bearings, formed in the ends of the main frame, a number of cross-heads, adjustably mounted on the companion bars, a plurality of driving-heads, supported in each of said cross-heads, and the operative connection for transmitting motion from the driving-shaft, substantially as described.

2. In a box-stapling machine, the combination with the longitudinal companion bars, adapted to have a vertical movement, of a number of cross-heads, adjustably mounted thereon, a plurality of driving-heads, adjustably supported by said cross-heads whereby the driving-heads have both a longitudinal and a transverse adjustment in changing the working position of the same, substantially as described.

3. In a box-stapling machine, the combination with a longitudinally-disposed support, having a vertical movement, of a number of cross-heads adjustably mounted thereon, and a plurality of driving-heads, mounted in each of said cross-heads and arranged in rows transversely, and means for positioning the driving-heads both with reference to the spacing of the staples and the distance between the corner-joints, substantially as described.

4. In a box-stapling machine, the combination with a cross-head, adjustably mounted, the operative connection for transmitting a vertical movement thereto, a rod, having its respective ends fixed in said cross-head, a staple-driver, a clip, providing a movable connection between said rod and driver, the staple-forming bars, a back guide, in which the driver and forming-bars are loosely framed, and means for movably supporting said back guide, substantially as described.

5. In a box-stapling machine, the combination with the driver and forming-bars, the back guide, the transverse bars 15 and 16, slotted longitudinally, the adjusting and locking bolts, engaging said back guide, the companion end plates, to which the respective ends of the transverse bars are secured, the front and back frame-bars, C C', slotted longitudinally, and the adjusting and locking bolts, inserted through the slotted bars C C' and engaging said end plates, substantially as described.

6. In a box-stapling machine, a main frame, provided in its respective ends with vertical guide-bearings, the longitudinal companion bars, the companion heads, moving in said guides, the driving-shaft, the companion rods, operatively connecting said heads and driving-shaft, a number of cross-heads mounted on said longitudinal bars, and a plurality of

driving-heads, supported from said cross-heads, substantially as described.

7. In a box-stapling machine, a driving-head, comprising a staple-driver, the wire-cutting and staple-forming bars, a transverse bar connecting the upper ends of the forming-bars, the curved arms, pivoted at their upper ends to the driver and normally engaging said transverse bar, means for disengaging said arms in arresting the down movement of the forming-bars, means for returning said arms to their normally engaged position, the back guide, in which the driver and forming-bars have a vertical movement, and an anvil-die, movably secured in the back guide and normally positioned in the path of the said driver, substantially as described.

8. In a box-stapling machine, the combination with the transverse bar, connecting the forming bars, of a bolt, fixed therein and passing through a vertical slot in the staple-driver, a face-plate a bolt, inserted in the face-plate, and a spring, having its respective upper and lower ends attached to said bolts, substantially as described.

9. In a box-stapling machine, the cutting and forming bars, having their lower ends beveled to an edge, of the companion die members, provided with grooves and with which the forming-bars are adapted to engage in severing the wire and sharpening both ends of the staple, and a wire-guide, normally located in the path of one of the forming-bars and adapted to be forced backward out of the way by the contact thereof at the proper time, and means for returning said guide to its normal position when the forming-bar shall have passed out of contact, substantially as described.

10. In a box-stapling machine, the combination with the lower front and back framing-bars, of the clencher-frame, comprising the companion side bars and the two end pieces, and means for changing the position of the clencher-frame in bringing the parts into alinement with the driving-heads, substantially as described.

11. In a box-stapling machine, the combination with the clencher-frame, adjustable longitudinally with reference to the main frame, of a clencher back guide, a clencher-plate, the clencher-dogs, a lifting-yoke, and means for periodically imparting a vertical movement thereto, substantially as described.

12. In a box-stapling machine, the combination with a back guide, adjustably supported in position, of a clencher-plate framed therein, the clencher-dogs, pivoted at one end and loose at the other, the loose ends resting on the clencher-plate, a yoke, upon which the clencher-plate is mounted, and provided with a stem; the lower end of which is bifurcated and loosely embraces the driving-shaft, and means for imparting a vertical movement to said yoke, substantially as described.

13. In a box-stapling machine, the combination with the clencher-frame, of a back guide, adjustably retained therein, a clencher-plate, the companion clencher-dogs, having curved concave engaging surfaces and pivoted at their outer ends to said back guide, the inner loose ends resting on the clencher-plate, and means for actuating the clencher-plate, substantially as described.

14. In a box-stapling machine, the combination with a back guide, of a clencher-plate framed therein and provided with vertical slots, of a detachable face-plate, provided with guide-pins engaging said slots in the clencher-plate, substantially as described.

15. In a box-stapling machine, the combination with the main frame, of a clencher-plate a retaining back guide, adapted to have both a longitudinal and a transverse adjustment with reference to the main frame, a yoke, on which the clencher-plate is mounted, said yoke being provided with a stem having a bifurcated lower end embracing the driving-shaft, a cam-wheel, mounted on the driving-shaft, and a roller, journaled in the yoke-stem and having a rolling contact with the periphery of the cam-wheel, substantially as described.

16. In a box-stapling machine, the combination with a shaft, 94, journaled in and extending along the front side of the main frame, the beveled pinions mounted thereon at intervals, the transverse counter-shafts, having pinions mounted on the front ends thereof which engage the pinions on shaft 94, a pinion, mounted on one end of shaft 94, a rack-bar, having its upper end engaging said pinion, and means for imparting a vertical movement to said rack-bar in actuating the wire-feed shafts, substantially as described.

17. In a box-stapling machine, the combination with the main wire-feed shaft, of the counter-shafts, receiving motion therefrom, a pinion, mounted on one end of the main feed-shaft, a rack-bar engaging said pinion, a link, connected with the rack-bar, and a shaft, whereby an intermittent rotary movement is transmitted to the wire-feed shafts, substantially as described.

18. In a box-stapling machine, the combination with the main frame, of the wire-feed shaft, journaled therein, the counter feed-shafts actuated thereby, the wire-feed rollers, mounted thereon, the tension-rollers, journaled above and in line with the feed-rollers, the angle-levers, for regulating the gripping action of the tension-rollers, and means for periodically imparting a rotary motion to said wire-feed shaft, substantially as described.

In testimony whereof I affix my signature in presence of two witnesses.

JOSEPH SCHMIDT, JR.
